UNITED STATES PATENT OFFICE.

HARRISON D. McFADDIN, OF EAST ORANGE, NEW JERSEY.

DESIGN FOR A LAMP SUPPORT.

Application filed October 19, 1927. Serial No. 23,803. Term of patent 7 years.

To all whom it may concern:

Be it known that I, HARRISON D. McFADDIN, a citizen of the United States, residing at East Orange, county of Essex, and State of New Jersey, have invented a certain new, original, and ornamental Design for a Lamp Support, of which the following is a specification, reference being had to the accompanying drawing, forming part thereof.

The figure is a perspective view of a lamp support showing my new design.

I claim:

The ornamental design for a lamp support as shown, and described.

HARRISON D. McFADDIN.
